UNITED STATES PATENT OFFICE.

LOUIS E. VALCOURT, OF PROVIDENCE, RHODE ISLAND, ASSIGNEE TO LOUIS STERN
CO., OF PROVIDENCE, RHODE ISLAND, A CORPORATION OF RHODE ISLAND.

BRACELET.

Application filed March 28, 1924. Serial No. 702,702.

To all whom it may concern:

Be it known that I, LOUIS E. VALCOURT, a citizen of the United States, residing at Providence, in the county of Providence and State of Rhode Island, have invented certain new and useful Improvements in Bracelets, of which the following is a specification.

This invention relates to improvements in the construction of bracelets or chains formed of a plurality of links flexibly connected together; and the object of this invention is the construction of such a bracelet or chain having links mounted to telescope one within the other to render the same extendible in the direction of its length.

A further object of this invention is to construct a series of outer links in box shape and a series of inner links in somewhat of a band shape to slide in the box links, whereby when extended only plain surfaces on the top and bottom of these slide links are exposed from either the front or back of the chain.

A further object of this invention is to pivotally connect the box link members with the slide link members whereby the bracelet or chain is rendered very flexible and a spring is provided to act upon these links to return them either when extended or flexed out of their normal contracted position.

With these and other objects in view, the invention consists of certain novel features of construction, as will be more fully described, and particularly pointed out in the appended claims.

In the accompanying drawings:

Figure 1 is a side elevation showing a portion of a bracelet of my improved construction as provided with hooks on its ends for attachment to a wrist watch.

Figure 2 is a perspective view in detail showing one of the outer box-shaped links which is preferably formed of a short length of tubing having bendable connecting fingers at either end.

Figure 3 is a perspective view showing the development of one of the inner links as cut from sheet stock.

Figure 4 shows the stock illustrated in Figure 3, as bent up into the form of a slide link, the ends of the folded member

being locked together by a tongue folded through an eye in the opposite end.

Figure 5 is a perspective view of a separate abutment member which is positioned and supported at one end of each box member and within the slide member to serve as a guide for the spring and a stop for limiting the spring compressing movement of the slide link.

Figure 6 is a sectional plan view of a number of the links assembled and the slide links partially drawn out from the box links.

Figure 7 is a central sectional edge view of the assembled parts illustrated in Figure 6.

Figure 8 represents both a top and a bottom view of reduced size showing the links extended and the plain surfaces of the slide links as being partially exposed.

Figure 9 is an edge view showing the links partially extended.

Figure 10 is a perspective view showing a link with an inturned connecting lip at either end.

Figure 11 is a perspective view showing a box link with an inturned connecting lip at one end and bendable fingers at the opposite end.

Figure 12 shows a spring connecting clip which serves to connect the inturned lips of two of these box links together.

Figure 13 shows two of the box links connected together by the spring clip.

It is found in the practical construction and operation of bracelets of this character to so form the parts that they may all be made automatically by machinery and bent or folded into shape and assembled or connected together without the use of solder, the heat of which detrimentally affects and discolors the finish of the stock, and the following is a detailed description of one construction by which these advantageous results may be accomplished:

With reference to the drawings, 10 designates the outer box-shaped links which may be constructed in any suitable way but which are preferably formed from a length of tubing, the same having a pair of ears 11 and 12 on opposite ends of its side walls.

The inner telescoping or slide link 13 is formed, preferably of sheet stock, as illustrated in Figure 3, having a slot 14 at one

end and a tongue 15 at its opposite end also this blank is provided with a pair of laterally-extending arms 16 at the center portion or fold thereof.

5 In forming this slide link this blank is folded at its center portion as illustrated in Figure 4, forming an end wall 17 at the fold, its free ends being shaped to lie one inside of the other and the tongue 15 is 10 passed through the opening 14 and is sharply bent or folded back over the stock of the other end to firmly lock these ends together.

15 The arms 16 are also folded inwardly toward each other to lie against the end wall 17 and their extremities are turned outwardly as at 18 forming a pair of convenient fingers for engaging or extending into the coils of the spring 19.

20 In connecting the box links to the slide links the fingers 12 on the box link are at one end folded inwardly, as best illustrated in Figure 6, to engage the double or reinforced end wall 20 of the slide link 18 25 thereby pivotally connecting the slide link to the box link permitting one to swing upon the other and obtain unusual flexibility in this chain or bracelet.

30 In order to provide a suitable abutment for the end of the coiled spring positioned opposite that which engages the arms 18, I have provided an abutment plate 21 best shown in Figure 5, which has a broadened base portion 22 positioned to rest against 35 the pair of inturned fingers 11 of the box link and this abutment member is provided with a pair of inwardly-extending arms 23 which are spaced apart for the reception of the spring 19 which is guided between them, 40 a central finger 24 being also provided to extend into this spring to assist in retaining it in the desired operating position.

These side arms 23 in addition to serving as guides for the spring are also adapted to 45 engage the end wall 17 of the slide link to limit the spring compressing movement of these links and so prevent the spring from becoming unduly compressed and injured.

50 It will be noted that by my improved construction of the members of the bracelet that the outer or box members may be readily formed of tubular stock if desired with the little ears or fingers formed integral at their ends. The inner or slide link 55 is so cut from sheet stock, that it may be folded into shape and locked into position by the bending of the tongues 15 through the eye 14, then the parts including the abutment and spring may be assembled one 60 within the other and the whole connected by simply bending inwardly the ears or fingers 11 and 12 of the box links.

65 In some instances it is found desirable to be able to readily connect or remove one or more links to or from the bracelet to change

its operating length to fit arms of different sizes and in order to accomplish this in a simple and practical way, I have provided links such as those illustrated in Figures 10 and 11 both of which are of the box type 70 and have the outward appearance of the rest of the links of the bracelet but which are not capable of being extended like those links. The link shown in Figure 10 is provided with an inturned lip 25 at either end 75 and is used exclusively as a spacing or enlarging link for the bracelet and that type illustrated in Figure 11 has an inturned lip 26 on one end and bendable connecting fingers 27 on its opposite end. Those links formed with the inturned lips 25 and 26 may be releasably connected together by means of the U-shaped spring connector 28 which is provided with an eye 29 of a width to receive both the lip 25 of one link and the lip 80 26 of the next link to lock them together in the manner shown in Figure 13. Usually two or three of these extra links are inserted into the center portion of a bracelet when new, to form it of maximum length 85 and may be readily removed to reduce its length to fit the arm of the wearer.

90 My improved chain or bracelet is very practical in construction and is very strong and durable and may be made very handsome and attractive in appearance and the broad exposed top and bottom surfaces of the inner links of the chain may also be ornamented to further render the device handsome and attractive in appearance.

95 The foregoing description is directed solely towards the construction illustrated, but I desire it to be understood that I reserve the privilege of resorting to all the mechanical changes to which the device is susceptible, the invention being defined and limited only by the terms of the appended claims.

100 I claim:

1. A bracelet structure comprising a series of box links, a slide link in each box link, 110 inwardly-projecting fingers on the end of the box link pivotally connecting it to the next adjacent slide link, and a spring acting between said links for normally causing the ends of said box links to abut.

115 2. An extendible bracelet structure comprising a series of box links, a band-shaped slide link in each box link, fingers extending inwardly from the opposite side walls of the box links adjacent their ends to pivotally engage one end of the next band-shaped adjacent slide link, and spring means acting between the box and slide links to cause the links to normally assume a contracted position.

120 3. An extendible chain structure comprising a series of box links, a slide link in each box link, each slide link being connected at one end to the next adjacent box link, 125 each of said slide links being formed of a

- strip of metal folded into band shape and disposed in its box link with its walls parallel to the back and front walls of the box, and integral interlocking means for securing the meeting ends of the band together. 5
4. An extendible chain structure comprising a series of box links in which are mounted to slide a series of slide links, a spring having an abutment at its opposite ends and acting between said box links and slide links to normally hold them contracted, said box links having a set of inturned fingers at either end, one set being for pivotally connecting it to the next adjacent slide link and the other set for supporting a spring abutment member. 10
5. A bracelet structure comprising a series of box links, a slide link in each of said box links having top, bottom, and end walls, a spring tending to house the slide link in its box link, a longitudinally inwardly-extending finger at one end of said slide link for extending and retaining an end of the spring, and a separate spring guiding member also positioned in the slide link and supported from its box to serve as an abutment and guide for the opposite end of the spring. 15
6. A bracelet structure comprising a series of box links and a slide link in each of said box links formed of a strip of metal folded to provide top, bottom, and end walls, a spring tending to house each slide link in its box, a longitudinally inwardly extending member integral with said slide link at its fold to extend into and guide one end of the spring and an abutment member supported by the box link for receiving the opposite end of said spring. 20
7. A bracelet structure comprising a series of box links and a slide link in each of said box links formed of a strip of metal folded to provide top, bottom, and end walls, a spring tending to house each slide link in its box, an inwardly-extending member integral with said slide at its fold to guide one end of the spring, and a separate abutment member supported by its inclosing box link having arms for receiving and guiding the opposite end of the spring. 25
8. A bracelet structure comprising a series of boxes, a strip of metal folded into band form to form a connecting link having top, bottom, and end walls with open sides and one normally housed in each of said boxes, fingers on one end of said boxes 55 for securing one end of the next adjacent link thereto, an abutment member in each of said links, fingers on the opposite end of said boxes folded inwardly through the sides of said links for engaging said member, and a spring acting between said member and link for yieldingly causing the ends of said boxes to abut. 60
9. An extendible bracelet chain structure comprising a series of box links, band connecting links carried by each box link, means for connecting each band link to one of its adjacent box links, guide members in each of said connecting links, fingers on said boxes engaging said member, a spring acting between said member and connecting link to yieldably draw the ends of said box links towards each other, and a stop carried by said guide member for limiting the expanding movement of said chain links. 65 70 75
10. A bracelet structure comprising a series of box links operatively connected through a series of slide links extendibly mounted therein, and a box link intermediate the ends of the bracelet having a pair of 80 inwardly-bendable fingers on both of its ends for engaging the next adjacent slide links on both of its ends.
11. A bracelet structure comprising a series of box links operatively connected 85 through a series of slide links extendibly mounted therein, and a plurality of removable box links connected intermediate the ends of the bracelets having inwardly extending portions clamped together. 90
12. A bracelet structure comprising a series of box links operatively connected through a series of slide links extendibly mounted therein, a plurality of removable box links connected intermediate the ends 95 of the bracelet having inwardly-extending portions clamped together, and a spring clamp engaging said inwardly-extending portions for releasably connecting their links together. 100

In testimony whereof I affix my signature.
LOUIS E. VALCOURT.
